Primary Examiner — Keith J Wilson

(74) Attorney, Agent, or Firm — Marshall, Gerstein & Borun LLP

(57) **CLAIM**

The ornamental design for a filter for pet fountain, as shown and described.

DESCRIPTION

FIG. 1 is a top, front, right side perspective view of a filter for pet fountain showing our new design;
FIG. 2 is a top, left, front side perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.
